UNITED STATES PATENT OFFICE

140,589

DESIGN FOR AN AUTOMATIC ACTUATOR FOR MOVABLE PARTS OF AN AIRPLANE

Raymond V. Bruland, North Hollywood, Calif., assignor to Lear, Inc., Piqua, Ohio, a corporation of Illinois

Application November 10, 1944, Serial No. 116,267

Term of patent 14 years

(Cl. D71—1)

To all whom it may concern:

Be it known that I, Raymond V. Bruland, a citizen of the United States of America, residing at North Hollywood, in the county of Los Angeles, in the State of California, have invented a new, original, and ornamental Design for an Automatic Actuator for Movable Parts of an Airplane, of which the following is a specification, reference being had to the accompanying drawings, forming a part thereof.

In the drawings:

Fig. 1 is a top plan view of an automatic actuator for movable parts of an airplane, embodying my new design.

Fig. 2 is a right end elevational view of the actuator shown in Fig. 1.

Fig. 3 is a left end elevational view of the actuator shown in Fig. 1.

Fig. 4 is a side elevational view of the actuator shown in Fig. 1.

I claim:

The ornamental design for an automatic actuator for movable parts of an airplane, substantially as shown.

RAYMOND V. BRULAND.
